Inventor:

UNITED STATES PATENT OFFICE.

WILLIAM HAWKS, OF DULUTH, MINNESOTA, ASSIGNOR TO HUGO MANUFACTURING COMPANY, OF DULUTH, MINNESOTA, A CORPORATION OF MINNESOTA.

BOILER-STAND.

1,245,228.

Specification of Letters Patent. Patented Nov. 6, 1917.

Application filed September 27, 1913. Serial No. 792,228.

To all whom it may concern:

Be it known that I, WILLIAM HAWKS, a citizen of the United States, residing at Duluth, in the county of St. Louis and 5 State of Minnesota, have invented certain new and useful Improvements in Boiler-Stands, of which the following is a specification.

This invention provides a stand of novel 10 formation adapted to support any of the usual sizes of upright cylindrical tanks employed in houses and elsewhere for storing heated water and commonly called "boilers", and it is so formed and arranged that 15 it is susceptible of use with boilers of different sizes without alteration. Thus there is avoided the necessity of providing stands in accordance with the dimensions of the boilers. Further, the stand is made of relatively few parts, which it is not necessary to 20 disassemble in attaching to or removing from a boiler.

The stand also is so formed that it has 25 as a part of its structure a T to which may be attached a supply-pipe leading from a range, furnace, gas-heater, or other place; and a drainage-cock, whereby, when the stand is connected to a boiler, there is at 30 the same time attached a pipe or conduit leading thereinto, and there is obviated the necessity of making an additional connection.

When read in connection with the description herein, the details of construction 35 and arrangement of parts contemplated by the invention will be apparent from the accompanying drawing, forming part hereof, wherein a preferable embodiment of the invention is disclosed, for purposes of illustration.

While the embodiment disclosed now is considered a preferable one, it is to be understood that changes can be made therein within the limits of the claims without departing 45 from the nature and spirit of the invention, and that it is not the intention to be limited necessarily to the exact form shown in interpretation of the claims.

Like reference-characters refer to corresponding parts in the views of the drawing, 50 of which—

Figure 1 is an elevation; and
Fig. 2 is a sectional view.

Referring more particularly to the drawing, 55 3 designates a base, in the top side

of which is a threaded opening or socket 4. The base preferably is of inverted bowl shape, and usually is made of metal. Into the socket 4 is screwed the lower threaded end of a standard size length of pipe 5 60 forming the pillar of the stand.

The upper portion of the stand includes a member 6, which comprises an interiorly-threaded sleeve 7 screwed over the upper end of the pillar 5 and an inverted T 65 consisting of a transverse section 8 and an upwardly-extending portion 9. The lower wall of the transverse portion 8 prevents communication with the sleeve 7, and the T contains passages through the transverse 70 portion and therefrom through the upwardly-extending portion. The upwardly-extending portion of the T is exteriorly threaded, and it has extending upwardly therefrom a smaller exteriorly-threaded 75 nipple 10. A substantially bowl-shaped outwardly-extending flange 11 having a threaded central opening is positioned on the exteriorly-threaded part of the portion 9 of the T, and in its lower part this flange 80 has straight sides 12 for engagement by a wrench or other similar tool.

When attached to a boiler, for example as shown in the drawing, the nipple 10 is 85 screwed into the opening usually in the center of the bottom end of domestic and other similar boilers, whereby communication between the boiler and the T is afforded. Then the flange is turned until its outer edge portion engages the bottom of the boiler in the 90 vicinity of its center around the nipple, whereby the weight of the boiler will be sustained by the T and the parts therebelow. The flange engages the bottom of the boiler where the greatest strain is imposed under 95 pressure, and thereby tends to prevent the bulging or sagging of the bottom under influence of weight and pressure that frequently occurs when the boiler is supported as in common practice at the circumferential 100 lower edge. One end of the transverse portion of the T is available for connection with a pipe 13 leading from a range, furnace, gas-heater, or other place, whereby the boiler is supplied with liquid through the 105 stand, and the other end is available for connection with a drainage-cock or valve 14. The stand being formed of standardized parts, ordinary water or gas pipe may be used to form the pillar portion, and the 110

stand may be made of any desired practicable height dependent upon the length of the pipe used as the pillar.

Having thus described my invention, what I claim as new, and desire to secure by Letters Patent, is—

1. A boiler-stand comprising a **T** having a transverse portion arranged for connection with a supply-pipe and a drain-valve and an upwardly-extending exteriorly screw-threaded portion having extending above its threaded part a smaller exteriorly-threaded nipple arranged for connection to the bottom of a boiler at its center, and a bowl-shaped outwardly-extending member on said threaded larger part of the upwardly-extending portion arranged to have its outer edge turned against the bottom of the boiler in the vicinity of the center around the nipple.
2. A boiler-stand comprising a **T** having a transverse portion arranged for connection with a pipe and a drain-valve and an upwardly-extending exteriorly screw-threaded comparatively large portion having extending above its threaded part a smaller exteriorly screw-threaded nipple arranged for connection to the bottom of a boiler at its center, and a bowl-shaped out-

wardly-extending member on said screw-threaded larger part of the upwardly-extending portion arranged to have its outer edge turned against the bottom of the boiler between its periphery and center and thereby to sustain the weight of the boiler between its periphery and center.

3. A boiler-stand comprising a **T** having a transverse portion arranged for connection with a pipe and drain-valve and an upwardly-extending exteriorly screw-threaded comparatively large portion having extending above its threaded part a smaller exteriorly screw-threaded nipple arranged for connection to the bottom of a boiler at its center, and an upwardly-flaring member surrounding and supported from said screw-threaded larger part of the upwardly-extending portion arranged to have its outer edge bear against the bottom of the boiler between its periphery and center and thereby to sustain the weight of the boiler between its periphery and center.

In testimony whereof, I affix my signature in the presence of two witnesses.

WILLIAM HAWKS.
